UNITED STATES PATENT OFFICE.

WILLIAM M. BRUCE, JR., OF SPRINGFIELD, OHIO.

WIRELESS TELEGRAPHY.

1,251,473.

Specification of Letters Patent.

Patented Jan. 1, 1918.

Application filed December 8, 1915. Serial No. 65,771.

To all whom it may concern:

Be it known that I, WILLIAM M. BRUCE, Jr., a citizen of the United States, residing at Springfield, in the county of Clark and 5 State of Ohio, have invented certain new and useful Improvements in Wireless Telegraphy, of which the following is a specification.

My invention relates to improvements in 0 wireless telegraphy and has for its object to provide means whereby the signals which are usually received on a telephone receiver can be relayed to an ordinary telegraph instrument, such as a sounder or recording 15 device.

In carrying out this invention I make use of a vibrating contact connected to a 20 vibrating diaphragm of a telephone or other receiving device and so arranged that the 25 said vibrations will cause the opening and closing of a circuit including ordinary translating devices during the long or short periods of vibration corresponding to dots and dashes.

25 In the drawings,

Figure 1 is a diagram.

Figs. 2 to 4 are detailed views of parts of the same.

In the drawings, *a* represents an ordinary 30 telephone receiver which is connected in the usual way in a wireless circuit. *a'* is the diaphragm of said receiver which vibrates in periods corresponding to dots and dashes from the high frequency current coming 35 into the receiver *a*. This receiver will be mounted upon a suitable frame (not shown) and there is attached to the diaphragm *a'* a fine thread-like connection *b*, the opposite 40 end of which is attached to an adjustable spring *b'*, suitably mounted in the frame work. To this thread-like connection *b* is attached one arm *c'* of a pivoted lever *c*, the pivot of which is marked *c''*, whose arms 45 *c''* and *c''* have attached thereto thread-like connections *c''* and *c''* which extend to a suspended bridle *d'*. This suspended bridle *d'* is preferably mounted within a suitable frame *d* on which is also mounted a vibrator *d''*. The suspension for the bridle *d'* 50 consists of thread-like connections *d''* and *d''* having proper tension adjustment in the usual way and to this bridle is attached a contacting arm *e* which is, by the vibrator *d''*, caused to vibrate vertically and by the connections above described from the diaphragm 55 *A'* to oscillate laterally in unison with the

vibrations of the diaphragm *a'*. The arm *e*, which is preferably provided at the outer end with a bent contacting portion *e'*, stands adjacent to contacts *e''* and *e''* between which is a neutral zone *e''* and opposite or adjacent to which the contacting arm *e'* normally vibrates. The contacts *e''* and *e''* are in circuit with a relay *f* and battery *X*. The circuit can be traced as follows: from contact *e''* and *e''* by wires 1 and 2 to relay *f*, wire 3, to battery *X* and wire 4 to the contacting arm. The relay *f* may be a polarized relay and has a local circuit from its armature *f'* through contact *f''* and by wire 5 to a sounder or recorder *s*, thence by wire 6 to battery *X'* and by wire 7 to the armature *f'* of the relay *f*.

I preferably provide means for supporting the vibrating lever *c* so that the movement of the lever *c* and the contacting arm *e* may be tuned so that the natural period of vibration of the contacting arm *e* will coincide with the number of vibrations actuating the receiver diaphragm and this I accomplish as shown in Fig. 4 by suspending the lever *c* by thread-like supports *c''*, *c''* and *c''*, one of these being preferably provided with a spring *c''*. For the supports *c''* and *c''* an adjustable spreader *c''* is 35 provided with means for holding it in fixed position at different adjustments to or from the lever *c*; these thread-like suspensions *c''* and *c''* being connected with an adjustable head *c''* by which the tension upon the supporting device may be properly adjusted. By adjusting the tension and spreader devices the vibrations of the contact arm can be properly tuned to the receiver vibrations.

The result of this construction is that so 35 long as the diaphragm *a'* of the receiver is normal the arm *e* is caused to vibrate by the vibrator *d''* to and from the neutral or zero point *e''* between the contacts *e''* and *e''*. Any vibration of the diaphragm causes the contact arm *e* to move at right angles to the normal vibrations and the combined movements of the arm cause it to engage the contacts *e''* or *e''*. No matter which contact is engaged a circuit will be closed from the 40 battery *X* through the relay *f* which will cause the relay to move against its contact *f''* and close the circuit for the sounder or other translating device and this will remain closed during the period of the vibration 45 which will be a short period for a dot and a longer period for a dash; the relay *f* being

biased so it will fall back as soon as the diaphragm vibrations cease.

For the contacts, I preferably employ mercury as I have found a more perfect contact is secured in this way. I preferably support these mercurial contacts so that the only space between them is an insulated neutral or zero point e^4 . The tendency of the liquid, such as mercury, to form in a globule being utilized so as to form a wall on each side of the neutral point as shown in Fig. 3. Apparatus of this kind has been demonstrated to be sufficiently sensitive to respond to the vibrations received on a diaphragm or ordinary telephone receiver and translate such vibrations into dots and dashes on an ordinary telephone recorder or sounder.

I have shown and described a polarized relay in the local circuit for operating the sounder or recorder, but this is not essential as various forms of relays can be used for this purpose. A sluggish relay which will be held up by the rapid making and breaking of the contact due to the vibrating of the arm e , but one which would respond to the makes and breaks between the vibrations, such as shown in my former Patent No. 1,073,886 would operate satisfactory.

I have used the word diaphragm as applied to a telephonic receiver and by this I mean to include any vibrating device which would respond to high frequency currents as does the diaphragm of a telephone receiver.

Having thus described my invention, I claim:

1. The combination of a diaphragm operatively connected to a wireless circuit, a suspended cradle, an intermediate operating arm connected with said diaphragm and said cradle, an electro-magnetic vibrating device, and a contacting arm connected to said cradle and vibrated by said vibrating device in unison therewith and in a different direction from that vibrated by the said diaphragm, substantially as specified.

2. In combination with an electromagnetic vibrating device, a contact arm connected to said vibrating device so as to vibrate in unison therewith in one direction, independent means for vibrating said arm in another direction, liquid contacts adja-

cent to said arm and adapted to be brought into electrical connection therewith by the double set of vibrations, said contacts being separated by a neutral zone and connected in a local circuit as and for the purpose specified.

3. The combination with a vibrating diaphragm, of a suspended bridle and means for connecting said diaphragm to said bridle, and a contacting arm on said bridle to respond to said vibration and independent means for causing said arm to vibrate at right angles to the plane of vibration of said arm when moved by said diaphragm, and contacts adjacent to said vibrating arm adapted to be engaged thereby by the two sets of vibrations as and for the purpose specified.

4. In a telegraph apparatus, a suspended contacting arm, and contacting devices adjacent thereto, a neutral or zero point between said contacting devices adjacent to which the said arm is normally located so it vibrates to and from said neutral point, a diaphragm receiver and a connection from said diaphragm to said suspended bridle to cause it to vibrate to a position adjacent to either of said contacts whereby the vibration of said diaphragm causes the arm to move to position adjacent to said contact and the independent vibration of said arm causes it to vibrate in contact therewith to complete the circuit as and for the purpose specified.

5. In an apparatus for wireless telegraphy, and in combination with a vibrating receiver, a connection from said receiver to a vibrating contact, means for causing said contact to independently vibrate in one direction and to vibrate in unison with the receiver in the other direction, said means involving devices for tuning the period of vibration of the contacting arm to coincide with the vibrations actuating the receiver, and contacting devices in circuit with a telegraph instrument whose circuit is closed by the combined movements of the contact arm.

In testimony whereof, I have hereunto set my hand this 22nd day of November 1915.

WILLIAM M. BRUCE, JR.
